CONVERTIBLE LOOM

John Gerhard Emanuel Klaesson,
Orebro, SwedenApplication January 21, 1949, Serial No. 71,780
In Sweden January 23, 1948

7 Claims. (Cl. 139—29)

1

This invention refers to a loom which is convertible into a table.

The object of the invention is to provide a handy and suitable loom, which, when not in use, in a simple manner can be converted into a table, making it possible to have and to use such a loom even in dwellings suffering from a lack of space. A great variety of looms, convertible into tables have earlier appeared on the market, but with most of them the conversion has proven to be a difficult task, and therefore they have become rather impractical.

The loom according to this invention comprises two side pieces, between which a warp beam, a cloth beam and a breast beam etc. are arranged, said side pieces being at their rear and front ends respectively provided with raised supports for a table top which is foldably attached to the rear of said supports. The invention is mainly characterized in that the batten, which carries the reed, is so arranged that, as the table top is respectively raised or lowered, said batten is automatically raised to its working position or lowered to a position permitting the table top to completely rest on the aforementioned side pieces. This is preferably effected by swingably journaling the batten in an intersection joint of a link system, so that when the table top is being raised, said batten is by means of a pulling bar, connected to the table top, pulled up to a suitable elevation. The invention is further characterized in that the pulleys of the shaft cords are placed at and underneath the table top so that when the table top is raised up the shaft cords occupy their proper positions. When the top is lowered, the shafts are laid over the batten and thus, like the rest of the loom parts, they are protected underneath said table top. A small amount of slack is given the warp so as to permit the lowering of the batten and the table top.

The loom according to the invention is thus ready for use by effecting two simple and natural operations, viz. the raising up of the table top and the stretching of the warp. The stretching as well as the slackening of the warp is achieved by turning the cloth beam. The invention will be more fully described below with references made to an embodiment shown on the attached drawing.

Fig. 1 shows a cross section end view of the loom with the table top shown in raised-up position, ready to be used for weaving;

Fig. 2 shows the loom with the table top in lowered position also in a cross sectional end view; and

2

Fig. 3 shows a perspective view of the whole machine.

The side pieces 1 are on their front and rear edges provided with raised supports 1a for the table top 2, and held together by either special cross bars or with the aid of some of the beams. A warp beam 3, a stretch beam 4, a breast beam 5 and a cloth beam 6, are in a known manner arranged between said side pieces. The table top 2 is with its cross bars 7 swingably mounted at 8 on the rear supports 1a of the side pieces. At each side of the loom just in front of the pivot point 8 a pull rod 9 is pivotally connected at its upper end to the cross bar 7 on the top 2. Said rod 9 extends inclinedly forward and downward towards the lower forward corner of the pertinent side piece, its lower end being hingedly connected to the lower end of an arm 11 carrying the batten 10, and also to the lower, free end of a link 12, hanging down pivotally from its respective side piece, said link being swingably journalled at 13.

Between the crossbars 7 and a short distance from the fore edge of the table top a rod 14 is arranged, which carries the heddles 15. The treadles 16, which operate the heddles are placed in the usual manner under the loom and with the rod 14 complete the shed arrangement.

In order to secure the top 2 so as to remain in its raised-up, or elevated position a pawl 17 is attached to each of the side pieces, said pawl being engageable with a notch in the pull rod 9 at the related side of the machine. On each of the side pieces there is also a brace 18 for the batten 10.

When the top 2 is in its raised-up position, the links 12, on account of the pull exerted by the pull rods 9, occupy a backwardly directed position, as in Fig. 1, and the batten is thus held in working position, in which the upper end of the batten will describe an arc entirely above the top edge of the side pieces at each stroke. The heddles 15 will then hang practically plumb from the rod 14.

When the loom is converted into a table, the top 2 is lowered after the warp has been given a small amount of slack, so that the batten is lowered to a location at which its upper edge is below the top line of the side pieces, and the shafts are placed over the batten, as in Fig. 2.

The invention is of course, not limited to the embodiment shown on the drawing, but a number of modifications are possible without deviating from the original, inventive idea. Thus the raising or lowering of the batten, effected by the

movement of the table top can of course be brought about by other means than those shown on the drawing. The table top may also be removable, leaving only the cross bars 7 to carry the pull rods 9 and the heddles 15.

Having now described my invention, what I claim as new and desire to secure by Letters Patent is:

1. A loom, which is convertible into a table, comprising two side pieces, a number of loom beams arranged between said side pieces, a table top, pivot means pivotally mounting said table top mounted at the rear upper end of both side pieces, and an erected batten mounted within said side pieces, said batten being elevatable from a storage position, in which it is kept below the upper edges of said side pieces so as to permit said table top to rest thereon, into a working position.

2. A convertible loom as claimed in claim 1, having the lower end of each batten arm hingedly connected to an intersection joint in a link system comprising a link swingably mounted on each side piece of the loom and a pull rod connecting the lower end of said link to the aforementioned table top, said pull rod being connected to said table top just in front of said pivot means mounting the latter.

3. A convertible loom comprising two side pieces, a number of loom beams between said side pieces, a shed arrangement including heddles and corresponding treadles under the loom for operating the heddles, and a table top swingably mounted at the rear upper end of both side pieces, said shed arrangement further including a rod for the heddles, said rod being mounted at and underneath said table top so that said heddles, when said table top is in an elevated position, are stretched substantially vertically from said rod to said corresponding treadles under the loom.

4. A loom convertible into a table, comprising two side pieces, a plurality of loom beams placed intermediate said side pieces, a table top pivotably mounted at one upper end of said pieces, a batten secured intermediate said pieces, and means link-

ing said batten with said table top and said pieces, whereby said batten may be elevated from a storage position under said table top in the non-elevated position thereof into a working position to extend above said pieces upon said top having been lifted.

5. A loom according to claim 1, further including a shed arrangement, said shed arrangement comprising heddles, corresponding treadles under the loom for operating the heddles and a rod for the heddles, said rod being mounted at and underneath said table top so that said heddles, when said table top is in an elevated position, are stretched substantially vertically from said rod to said corresponding treadles under the loom.

6. A loom according to claim 4, further including a shed arrangement, said shed arrangement comprising heddles, corresponding treadles under the loom for operating the heddles and a rod for the heddles, said rod being mounted at and underneath said table top so that said heddles, when said table top is in an elevated position, are stretched substantially vertically from said rod to said corresponding treadles under the loom.

7. A loom convertible into a table, comprising two side pieces, a table top pivotably mounted at one upper end of said pieces, a batten secured intermediate said pieces, a shed arrangement, means linking said shed arrangement to said table top and means linking said batten to said side pieces, whereby movement of said top is translated to said arrangement and said batten.

JOHN GERHARD EMANUEL KLAESSON.
